HANGER RACK

Edwin E. Wasil, Los Angeles, Calif.
(7814 State St., Huntington Park, Calif. 90257)

Filed Sept. 6, 1968, Ser. No. 13,411

Term of patent 14 years

Int. Cl. D6—01

U.S. Cl. D33—17

FIG. 1 is a perspective view of a hanger rack showing my new design;

FIG. 2 is a front elevational view thereof;

FIG. 3 is a rear elevational view thereof;

FIG. 4 is an elevational view taken from one side thereof;

FIG. 5 is a top plan view thereof; and

FIG. 6 is a bottom plan view thereof.

I claim:

The ornamental design for a hanger rack, as shown.
